(57) CLAIM

The ornamental design for a light mount, as shown and described.

DESCRIPTION

FIG. 1 is a perspective view;
FIG. 2 is another perspective view;
FIG. 3 is another perspective view;
FIG. 4 is a top view;
FIG. 5 is a bottom view;
FIG. 6 is a front view;
FIG. 7 is a back view;
FIG. 8 is a left side view; and,
FIG. 9 is a right side view.

The broken lines immediately adjacent the shaded areas represent the bounds of the claimed design while all other broken lines are directed to environment and are for illustrative purposes only; the broken lines form no part of the claimed design.
